UNITED STATES PATENT OFFICE.

HARRY HUSKEY, OF PHILADELPHIA, PENNSYLVANIA, ASSIGNOR TO SMITH, KLINE & FRENCH COMPANY, OF PHILADELPHIA, PENNSYLVANIA, A CORPORATION OF PENNSYLVANIA.

DESIGN FOR A TABLE.

47,821.

Specification for Design.

Patented Sept. 14, 1915.

Application filed March 5, 1915. Serial No. 12,432. Term of patent 14 years.

To all whom it may concern:

Be it known that I, HARRY HUSKEY, a citizen of the United States, residing in Philadelphia, county of Philadelphia, and State of Pennsylvania, have invented a new, original, and ornamental Design for a Table, of which the following is a specification, reference being had to the accompanying drawings, which form a part thereof.

The figure is a perspective view of a table embodying my new design.

The table embodies a support including a central flat-sided pedestal and radiating horizontally extending supporting feet and a show-case surmounting the pedestal, the show case comprising a bottom having a polygonal contour, with sides, formed of

flat glass plates, corresponding in number to the number of straight edges in the case bottom, and a circular glass top; the bottom and glass top projecting substantially beyond the glass sides and forming respectively a projecting ledge and overhanging rim.

I claim—

The ornamental design for a table as shown and described.

In testimony of which invention, I have hereunto set my hand, at Philadelphia, on this 2nd day of March, A. D. 1915.

HARRY HUSKEY.
